UNITED STATES PATENT OFFICE.

EDWARD DOWNING, OF BRATTLEBOROUGH, VERMONT, ASSIGNOR TO J. ESTEY & CO., OF SAME PLACE.

DESIGN FOR AN ORGAN-CASE.

Specification forming part of Design No. **11,374**, dated August 26, 1879; application filed July 25, 1879.
[Term of patent 7 years.]

To all whom it may concern:

Be it known that I, EDWARD DOWNING, of Brattleborough, in the county of Windham and State of Vermont, have produced an Improved Design for Organ-Cases, which I have assigned to J. ESTEY & Co., of Brattleborough, aforesaid, and of which the following is a specification, reference being had to the accompanying representation of the case.

The back board of the organ-case is extended upward, forming a superstructure, A, whose top rises to a considerable height above the key-board, and is provided in its center with a semicircular or arched cornice or molding, *a*, which is also extended laterally and horizontally each side of the arched portion. A short distance beneath the horizontal portions of the cornice *a* is a straight horizontal molding, *b*, and just above this is a boss or rosette, *c*, arranged in about the center, from which the circular top of the board A is struck. The space between the cornice *a* and molding *b* is filled with a design in lines, as shown, which may be produced by carving, painting, or inlaying.

Below the cornice *a* the back board, A, of the case has substantially vertical sides, formed in ornamental curves, and just above the top of the organ proper it is provided with wings *d d*, extending to the end walls of the case, and each ornamented by a semicircular molding, *e*.

Below the cross-molding *b*, and between the wings *d d*, is arranged a music-holder or pocket, B, consisting of a front board ornamented by a design, as shown, preferably formed by perforating through it, and of two side pieces, which hold said front board off from the back board, A. A horizontal bar, *f*, stands across the front board of the music-holder, and is supported off from and in front of the same by ornamental brackets *p p*, springing from the holder.

The ends C C of the case have front and back stiles *g g*, extending from top to bottom, which are separated by a shallow groove from a raised panel, *h*, between them, which also extends from top to bottom, and which is ornamented with a design in lines, as shown.

Projecting in front of the ends are the consoles D D, which are formed with an inclined front edge, *i*, just above the key-board, terminating in a slight swell or rounded corner, and descending thence vertically at *j* in a series of waves or reverse curves to *k*, where it recedes, and from which it descends in a concave curve to the approximately circular formation or boss *l*. Just above this boss the front portion of the console is insulated from its rear portion, or from the case end, by a dividing aperture through the console, and the boss or formation is further ornamented by having upon its inner or outer faces, or both, a circular molding, turned rosette, or medallion. From the back of the boss or formation a straight bar or leg, *m*, descends at an angle to the front of the base of the console, which it joins with a short concave curve. This oblique leg is preferably insulated from the part behind it by a triangular space.

The front of the case is divided by two vertical moldings, *n n*, extending upward from the pedal-brackets into three panels, E E, which may be embellished by ornaments *o o*.

Having described my improved design, what I claim as new therein, and desire to secure by Letters Patent, is as follows:

1. The design for the superstructure A of an organ-case, consisting of the arched and flat top, provided with cornice *a*, boss or rosette *c*, and molding *b*, with the wings *d d*, capped with arched moldings *e e*, substantially as set forth.

2. The design for the music-holder, composed of the ornamented front board, B, the bar *f*, and the brackets *p p*, substantially as described, and shown in the accompanying illustration.

3. The design for the end of the case, consisting of stiles *g g*, with the console D, springing from the front stile, in connection with the raised panel *h* between them, extending from top to bottom of the end of the case, and ornamented with the design in lines, substantially as described, and shown in the accompanying illustration.

4. The design for the consoles D, consisting of the base, the oblique bar or leg *m*, rising

(over)

from the front thereof, and extending to behind a circular formation, *l*, which bears a rosette, boss, or medallion, the projecting surface *k*, the waved vertical surface *j*, and the inclined receding surface *i*, all substantially as described, and shown in the accompanying illustration.

In witness whereof I have hereunto signed my name in the presence of two subscribing witnesses.

EDWARD DOWNING.
